CLAIM

U.S. PATENT DOCUMENTS

The ornamental design for a handle for a ground working implement, as shown and described.

DESCRIPTION

U.S. patent application Ser. No. 14/547,653, filed Nov. 19, 2014 is incorporated herein by reference in its entirety.

FIG. 1 is a left front upper perspective view of a handle for a ground working implement, showing our new design; FIG. 2 is a right rear upper perspective view thereof; FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof;

FIG. 8 is a bottom plan view thereof; and,

FIG. 9 is a right rear lower perspective thereof.

The broken lines shown in the drawings represent unclaimed environment only and form no part of the claimed design.

1 Claim, 9 Drawing Sheets
